UNITED STATES PATENT OFFICE.

JOSEPH WHARTON, OF MONONGAHELA, PENNSYLVANIA.

MANUFACTURE OF SHEET-GLASS.

No. 841,752.

Specification of Letters Patent.

Patented Jan. 22, 1907.

Application filed August 1, 1906. Serial No. 328,662.

To all whom it may concern:

Be it known that I, JOSEPH WHARTON, a citizen of the United States, residing at Monongahela city, in the county of Washington and State of Pennsylvania, have invented certain new and useful Improvements in the Manufacture of Sheet-Glass; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to a new and useful improvement in glass-machines, being particularly designed and constructed for the manufacture of plate, window, sheet, cathedral, and all other forms of a similar nature.

The fundamental idea involved in my invention is the construction of such a device that will simplify the manufacture of the foregoing-enumerated forms of glass, the process contained in my invention being easy to operate and can be constructed and maintained at a minimum of expense.

In the accompanying drawings in three sheets, forming a part of this specification, I have shown several detailed views of my invention, Figure 1 being a diagrammatical view of the heating-kiln part of the device. Fig. 2, Sheet 2, is a side elevation of the water-cooled pan used in my invention as attached to an overhead-carrier means. Fig. 3 is a top plan view of said pan. Fig. 4 is a similar view of a trimming-knife. Fig. 5 is a side elevation of the same. Fig. 6 is a cross-sectional view of the kiln having a glazing-compartment formed therein, one of the buggies supporting a revolving table being also shown, together with cam-lever means for elevating the glass from the table. Fig. 7, Sheet 3, is a detailed elevation showing method of removing glass from the pan to the revolving table. Fig. 8 is a cross-section of one of the buggies, showing means employed for elevating the glass from the table. Fig. 9 is a cross-section of the pan, and Fig. 10 a perspective of the carrier used to convey the glass from the pan to the revolving table.

Throughout the drawings the numeral 1 indicates brickwork forming the outside shell of the heating-kiln part of my invention, which is constructed in the well-known

manner common to devices of a similar character. Inside of this shell and at a predetermined distance therefrom is an inclosed circular arched passage-way 2. Operatively arranged in this circular passage-way is a table 3, supported on suitable buggies 4, which run on tracks 5. Arranged at suitable intervals on this revolving table are the stones 6, upon which the plates of glass 65 rest when going through the several steps of the process. The table 3 is operated by means of a rack 7 and meshing pinions 8, geared to a motor-driving means, or any other suitable and convenient plan for rotat- 70 ing this table may be adopted.

At a convenient point in the arched passage-way 2 is arranged a glazing-compartment 9, the same being constructed as tight as possible, only leaving sufficient clearance 75 for the revolving table 3. This aforesaid compartment is the primary and essential feature which I employ in my devices to reheat the plates of glass and bring back the brilliancy. Entering this compartment are 80 gas-supply pipes 10, so arranged that the flame will not come into contact with the glass plate, but will be so deflected that the heat from said flame will be directed onto said plate. Also arranged in this compartment is a 85 damper 11, also a peep-hole 12, which is in direct vision with a similar hole 13 formed through the shell 1.

Entering the passage-way 2 contiguous to the glazing-compartment 9 and above the 90 table 3 are suitable guides or tracks 14, upon which is mounted a skeleton carrier 15, the detailed plan of which is shown in Fig. 10. At the outer end of this carrier is a strip of angle-iron 16, in which the plate of glass is 95 intended to rest during the reversing process, the operation of which will be further described hereinafter. Communicating through the shell 1 with the interior of the furnace is an ordinary leer 17, having operatively ar- 100 ranged therein a plurality of oscillating cam-operated lifting-rods 17', which are designed to enter through the wall of the passage-way 2 and remove the sheet of glass from off the last stone in the series.

Operatively arranged in each buggy 9 is a means for elevating the plates of glass from the stone 6, and consists of a pair of rods 18, seated in recesses formed in said stone and having connected therewith rods 19 and 20, the latter having their lower ends connected with a bearing-plate 21. The method I em-

ploy to raise the rods 18 consists of a lever 22, pivotally arranged at any convenient point adjacent the furnace, the same being connected by a rod 23 with a lever 24, with which is in turn connected an arm 25, having a projecting portion 26, adapted to engage against the bearing-plate 21. While this means for raising the glass plate is satisfactory to the requirements of my invention, I do not wish to limit myself to the details as shown and described, as other just as satisfactory means can be substituted.

The pan employed in my invention consists of a hollow casting 27, slightly tapering toward the outer end, the under side of this end portion being rounded off in order to facilitate the dipping process. The inside of this pan is recessed to any desired depth conforming in all particulars to the size, shape, and thickness of the plate of glass desired. Communicating with the hollow interior of this pan are pipes, or, if preferred, pieces of flexible hose 28 and 29, one being intended to supply said chamber with water and the other to carry off the same, thus providing a continual circulation in order to keep the pan as cool as possible. A suitable handle 30, secured to the rear portion of the pan and suspended by means of a rope or chain with an overhead buggy 31, affords a means for operating the pan in any manner desired.

The cutting or trimming means that I employ, but which likewise can be modified to suit existing conditions, consists of a suitable supporting-framework 32, upon which is mounted a lever operated and weighted set of three knives 33, 33', and 33''. The knives 33 and 33' extend longitudinally of the supporting-frame, while the knife 33'' extends transversely thereof and is carried by the knives 33 and 33'. This arrangement provides a cutting or trimming device that will quickly and accurately shear off the filmy layer of glass from both sides and the end and abuts the tapered front of the dipping-pan in order that the sheet of glass on being reversed prior to the reheating process will have practically clean edges. The manner of operating the knives is optional, the manner shown being considered the most expeditious.

In the operation of my invention the glass is first melted and brought to the proper consistency in a suitable tank 34. The next step in the operation consists in dipping the hollow pan 27 into the tank to such a depth that upon withdrawal the recessed portion of said pan will be completely filled with the molten mass. It will be readily apparent that owing to the overhead-carrier arrangement to which the pan is connected the operator can swing said pan in any required position while in the act of dipping into the tank, and then again when the pan is moved with its recessed portion filled with

molten glass it can easily be run to the cutting-table prior to the second step in the process. During the passage of said pan from the tank to the cutting-table the glass has had time to set properly, and by the time it is ready for the trimming process the plate has partially solidified. The pan is now placed on a suitable support, and by means of a lever arrangement, as shown in Fig. 5, or any other suitable operating means the triple knives are made to descend and trim off the filmy layer of glass from the two sides and lower end of the sheet.

During the first two steps in the process the molten glass has been prevented from adhering to the metal pan, owing to the well-known fact that molten glass will not stick to a water-cooled body of iron. There will be a continual circulation of water through the interior of the pan whenever in use. The side of the glass plate that has come in contact with the body of iron will naturally become chilled and be given a more or less frosted appearance. The only way to overcome this defect and restore the entire sheet to a uniform brilliancy and glow is by reheating this frosted side, and hence the necessity for the following steps in the process. This pan containing the sheet of glass is next run forward to a point opposite the track 14 and the carrier 15 is run out to the edge of said track. Both carrier and pan are next tilted forward, so that the plate of glass will be resting against the top of the carrier and in the angle-iron 16, assuming a position shown in Fig. 7. The carrier is then tilted back to its normal seat on the track with the pan on top, and as soon as the plate has left its seat in the pan the latter is removed and returned to the tank for the subsequent dipping process. The first sheet of glass is then run into the passage-way 2, directly over the table 3, an opening of just sufficient clearance in height and width having been made through the walls of the shell 1 and passage-way 2. The next step is to lift the sheet of glass clear of the carrier in order that the latter may be withdrawn for the purpose of receiving the next succeeding sheet. This movement is accompanied by pushing on the lever 22, thus drawing on the rod 23, operating the lever 24, in order that the angled part 26 of the arm 25 will exert a pushing movement on the plate 21, and by so doing will raise the rods 18, which will operate between the bars of the carrier and lift the sheet in suspended position. The carrier is then withdrawn and the sheet lowered onto the stone 6 by releasing the hold on the lever 22. The table 3 is next made to revolve by means of the motor and meshing pinions and rack until the buggy on which rests the sheet of glass is positioned in the glazing-compartment 9, where the sheet is again elevated by means of the rods and method aforesaid.

The heat generated in this chamber is sufficient to remove the frosted appearance from the glass and diffuse an equitable brilliancy and glow throughout the entire sheet. The 5 table is again made to revolve until the next succeeding sheet enters the reheating or glazing chamber, and this operation being continued the sheets of glass will be gradually cooled off as they recede from the glazing-compartment until upon reaching a point opposite the leer 17, when the sheet is again raised from the stone by means of the lever movement heretofore described, and thus permit the sheet to be drawn into 15 the leer, where a more systematic cooling-off process is obtainable.

In order to afford a means for reducing the temperature in the furnace, I have provided one or more draft-openings 34 through the 20 brickwork 1. Through the shell 1 adjacent the inner end of the leer is a gas-supply pipe 35, thereby providing a means for heating said leer.

The rods 18, utilized to raise and lower the 25 sheets of glass during the several steps of the operation, are covered with some heat-resisting substance and so arranged and constructed as regards size and form that there will be no danger of the rods leaving an im- 30 press or of cracking the sheets of glass.

Having thus fully shown and described my invention, what I claim as new, and desire to secure by Letters Patent, is—

1. In a device of the character described, a 35 water-cooled pan having a central recessed portion to conform to any desired size, shape, or thickness of glass; means for reversing the sheet of glass molded in the pan and for re-heating the same to a uniform brilliancy; 40 substantially as described and shown.

2. In a device of the character described, a water-cooled pan having a central recessed portion to conform to any desired size, shape, or thickness of glass; overhead means for 45 suspending and manipulating said pan; cutting means for trimming the edges of the glass sheet; means for reversing the sheet of glass molded in the pan and means for re-heating the same to a uniform brilliancy; 50 substantially as described and shown.

3. In a device of the character described, a water-cooled pan having a central recessed portion to conform to any desired size, shape, or thickness of glass; overhead means for 55 suspending and manipulating said pan; cutting means for trimming the edges of the glass sheet; means for reversing the sheet of glass molded in the pan; carrier means for introducing said glass sheet into a reheating- 60 compartment; substantially as described and shown.

4. In a device of the character described, a dipping-pan having a cored-out compartment formed therein; means for introducing 65 water to and from said compartment; a re-

cess formed in the top of said pan to conform to any desired size, shape, or thickness of glass; and a suitable handle on said pan; as and for the purpose set forth.

5. In a device of the character described; a 70 suitable heating-kiln; a turn-table operatively seated in a covered passage-way inside said kiln; a reheating-compartment formed in a portion of said covered passage-way; a leer communicating with the kiln; tracks 75 entering the covered passage-way above the table upon which is mounted a buggy and means for rotating said table; as and for the purpose set forth.

6. In a device of the character described, a 80 suitable heating-kiln having a circular covered passage-way formed therein; a turn-table operatively mounted on tracks inside the covered passage-way; suitable stones mounted on said table; a reheating-compartment formed in a portion of said passage-way; tracks entering the passage-way above the table upon which is mounted a buggy; a 85 leer communicating with the kiln and passage-way; means for rotating said table and 90 means for regulating the heat throughout said kiln; as, and for the purpose set forth.

7. In a device of the character described, a 95 water-cooled dipping-pan having a central recessed portion to conform to any size, shape, or thickness of glass; a suitable heating-kiln having a circular covered passage-way formed therein; a turn-table operatively mounted on tracks inside the passage-way; means for rotating said table; suitable 100 stones mounted on said table; a reheating-compartment formed in a portion of said passage-way; tracks entering the passage-way above the table upon which is mounted a buggy; means for reversing the sheet of 105 glass molded in the pan onto the buggy and conveying same to the reheating-compartment; as, and for the purpose set forth.

8. In a device of the character described, a 110 water-cooled dipping-pan having a central recessed portion to conform to any size, shape, or thickness of glass; overhead means for suspending and manipulating said pan; a suitable heating-kiln having a circular covered passage-way formed therein; a turn-table operatively mounted on tracks inside the passage-way; means for rotating said 115 table; suitable stones mounted on said table; a reheating-compartment formed in a portion of said passage-way; tracks entering the 120 passage-way above the table on which is mounted a buggy; means for reversing the sheet of glass molded in the pan onto the buggy; means connected with the revolving table and passing up through each stone 125 mounted thereon for lifting the sheet of glass clear of the buggy and for elevating said sheet of glass above the stone; as, and for the purpose set forth.

9. In a device of the character described, a 130

- water-cooled dipping-pan having a central recessed portion to conform to any size, shape, or thickness of glass; overhead means for suspending and manipulating said pan; 5 cutting means for trimming the edges of the glass sheet; a suitable heating-kiln having a circular covered passage-way formed therein; a turn-table operatively mounted on tracks inside the passage-way; means for rotating said table; suitable stones mounted on said table; a reheating-compartment formed in a portion of said passage-way; tracks entering the passage-way above the table on which is mounted a buggy; means for reversing the 10 sheet of glass molded in the pan onto the buggy; lever and cam operated rods passing up through each stone for the purpose of lifting the sheet of glass clear of the buggy and for elevating said sheet of glass above the 15 stone; as, and for, the purpose set forth.
10. In a device of the character described, a water-cooled dipping-pan having a central recessed portion to conform to any size, shape, or thickness of glass; overhead means 20 for suspending and manipulating said pan; cutting means for trimming the edges of the glass sheet; a suitable heating-kiln having a circular covered passage-way formed therein; a turn-table operatively mounted on tracks 25 inside the passage-way; means for rotating said table; suitable stones mounted on said table; a reheating-compartment formed in a portion of said passage-way; tracks entering the passage-way above the table on which is 30 mounted a buggy; means for reversing the sheet of glass molded in the pan onto the buggy; means connected with the revolving table and passing up through each stone mounted thereon for lifting the sheet of glass 35 clear of the buggy and for elevating said sheet of glass above the stone; and a leer communicating with the kiln and passage-way; as, and for, the purpose set forth.
11. In a device of the character described, 40 a mold and means for elevating and reversing the glass molded therein and for reheating the same.
12. In a device of the character described, 45 a mold, means for suspending and manipu-
- lating said mold, means for reversing the glass in the mold, and means for reheating said glass.
13. In a device of the character described, a heating-kiln, a table rotatable therein, means for depositing glass upon the table, 50 and means for elevating the glass deposited thereon.
14. In a device of the character described, a heating-kiln, a table rotatable therein, means for depositing glass upon the table, 55 and means operative from the exterior of the kiln for elevating the glass deposited thereon.
15. In a device of the character described, a heating-kiln, a table rotatable therein, means for depositing glass upon the table, 60 and means movable through the table for elevating the glass deposited thereon.
16. In a device of the character described, a heating-kiln, a table rotatable therein, means for depositing glass upon the table, 65 elevating means for the glass carried by the table and mechanism for operating the elevating means.
17. In a device of the character described, a mold, means for trimming the glass molded 70 therein and means for reheating the same.
18. In a device of the character described, a mold, and means for trimming the edges of the glass molded therein.
19. In a device of the character described, 75 a mold, and means for simultaneously trimming the edges of the glass molded therein.
20. In a device of the character described, a mold, and means for simultaneously trimming the sides and ends of the glass molded 80 therein.
21. In a device of the character described, a heating-kiln, a glazing-compartment therein, a table movable in the kiln and through the compartment, means for depositing glass 85 upon the table and means for elevating the glass within the compartment.
- In testimony whereof I affix my signature in presence of two witnesses.
